UNITED STATES PATENT OFFICE

2,465,863

CONVERTIBLE STUDIO BED

Martin Fox, Chicago, Ill., assignor to The Seng
Company, a corporation of Illinois

Application November 5, 1945, Serial No. 626,726

6 Claims. (Cl. 5—59)

1

This invention relates to convertible beds, and more particularly to beds of the type that may serve as a convertible couch, with a compartment in the rear of the back rest for holding pillows, blankets, and the like.

The primary object of the invention is to provide an improved convertible studio bed wherein the bed section is horizontal when in bed-forming position, but is automatically inclined downwardly and rearwardly when in sitting position, so as to be more comfortable for the occupant.

A further object of the invention is to provide an improved mechanism and counterbalancing springs, so that the bed may be converted into a couch, or back to a bed, with a minimum of effort.

The invention is illustrated in a preferred embodiment in the accompanying drawings, in which—

Figure 1 is a front elevational sectional view, taken as indicated at line 1—1 of Fig. 2; Fig. 2, an elevational sectional view, taken as indicated at line 2—2 of Fig. 1; Fig. 3, a vertical sectional view, similar to Fig. 2, but showing the device in sitting position; Fig. 4, a plan sectional view, taken as indicated at line 4—4 of Fig. 2; Fig. 5, a fragmentary vertical sectional view similar to Fig. 3, but showing a modified hinge between the back rest and shelf; Fig. 6, a fragmentary sectional view similar to Fig. 5, showing the pillow compartment in open position; Fig. 7, a fragmentary vertical sectional view showing the modified device in bed-forming position; Fig. 8, a fragmentary plan view of the slide-hinge; and Fig. 9, a fragmentary sectional view, taken as indicated at line 9—9 of Fig. 8.

In the embodiment illustrated, a supporting frame, preferably of wood, has end portions 5 connected by a longitudinal bar 6 and a back section 7. The structure may have suitable legs 8, and is provided at each end with fixed stop members 9, on which the rear portion of a bed section 10 rests when in sitting position, as shown in Fig. 3.

The bed section 10 is preferably in the form of a rectangular frame made of angle iron, to receive a box spring and cushion, or mattress. The front portion of the bed frame is pivotally supported at 11 by means of a bracket 12, secured to the ends 5 of the supporting frame. A shelf member 13 is hinged at 14 to the top of the back 7. A suitable upholstered back rest 15 is hinged to the shelf member 13, as indicated at 16. Each end of the back rest is provided at its lower edge portion with a pitman 17 making a

5 pivotal connection 18 with the back rest, and a pivotal connection with the supporting frame at 19. Preferably, the pitman is bent, so that a pivot 20 is offset from a line drawn between the pivots 18 and 19. A pair of supporting links 21 are pivotally connected at 22 to the rear portion of the bed section and extend up to the pivots 20 on the pitmans 17. The links 21 are provided with forwardly extending fixed arms 23, to which 10 are secured tension springs 24, which extend upwardly and rearwardly and are secured to the back section, as indicated at 25. By this arrangement, it will be understood that the springs help to raise the back rest 15 to the position shown in Fig. 2 and in moving into the latter position the pivot 20 swings over the center of pivot 19, so that the device is self-locking in the position shown in Fig. 2.

If desired, the back section 7 may be closed 20 with a light panel and when the device is in sitting position, as shown in Fig. 3, a pillow compartment is formed between the back 7, the shelf 13, and the back rest 15.

In the modification shown in Figs. 5—9, the 25 structure is the same as described above, except that a special slide-hinge 26 has been provided to facilitate access to the bedding compartment back of the back rest 15, when the device is in couch position. One leg 27 of the hinge is secured to the back rest and is provided with a pin-receiving aperture 28. A bail-like slide member 29 is pivotally connected to the leg 27, and its rear end portions make a slidable connection with a bracket 30 which is secured to the shelf 30 member 13. This enables the back rest to be drawn forwardly from the position shown in Fig. 5 to the position shown in Fig. 6, so that bedding may be inserted in the opening. A pin or stud 31 is fixed to the bracket 30 and is arranged so that when the back rest is raised to the position shown in Fig. 7, it will extend to the opening 28 and prevent the back rest from being slid upwardly with respect to the shelf 13, and prevent it from falling forwardly when the device is in bed position. However, the pin does not prevent or interfere with conversion of the device from bed to couch, or return.

It will be noted that in transforming the device from a couch into a bed it is not necessary to pull the supporting frame away from the wall, as the shelf 13 and back rest 15 are brought into adjacent positions by substantially parallel movement and do not travel back of the plane of the fixed back 7 of the structure.

The foregoing detailed description is given for

clearness of understanding only, and no unnecessary limitations should be understood therefrom, for some modifications will be obvious to those skilled in the art.

I claim:

1. A convertible studio bed comprising: a supporting frame with a back; a bed frame movably mounted in said supporting frame so that it may be tilted back and forth from a horizontal bed-forming position into a downwardly and rearwardly inclined seat-forming position; a shelf member hinged to the back of the supporting frame so as to be substantially horizontal when the bed frame is in inclined position; a back rest having its top portion hinged to said shelf member and its lower portion linked to said supporting frame by pitmans substantially parallel to the shelf member so that said back rest may be swung up from a front rearwardly inclined position to a rear upright position adjacent to the back of the supporting frame; and a pair of links connecting the pitmans to the bed section so that movement of the back rest to upright position will move the bed section to horizontal position.

2. A convertible bed as specified in claim 1, in which the front portion of the bed section is pivotally connected to the supporting frame and stops are provided on the supporting frame to hold the rear portion of the bed section when lowered to inclined position.

3. A convertible bed as specified in claim 1, in which tension springs are connected to the connecting links and to the back of the supporting frame to facilitate movement from inclined position to horizontal position.

4. A convertible bed as specified in claim 1, in which the upper pivotal connections of the links to the pitmans are disposed in front of the rear pivotal connections of the pitmans to the supporting frame when the bed frame is in inclined position, and said upper pivotal connections move upwardly and rearwardly to a position adjacent to the back of the supporting frame and back of said rear pivotal connections

of the pitmans when the bed frame is raised to horizontal position.

5. A convertible studio bed comprising: a supporting frame with a back; a bed frame movably mounted in said supporting frame so that it may be tilted back and forth from a horizontal bed-forming position to a downwardly and rearwardly inclined seat-forming position; a shelf member hinged to the back of the supporting frame so as to be substantially horizontal when the bed frame is in inclined position; a back rest having at its top portion a hinge making a slideable connection with said shelf member so that an opening may be made between said back rest and the shelf member when the latter is in horizontal position, and said back rest having its lower portion linked to said supporting frame by pitmans substantially parallel to the shelf member so that said back rest may be swung up from an advanced rearwardly inclined position to a rear upright position adjacent to the back of the supporting frame; and a pair of links connecting the pitmans to the bed section so that movement of the back rest to a rear upright position will move the bed section to horizontal position.

6. A convertible bed as specified in claim 5, in which a stud is provided on the shelf member so as to engage a hole provided in the back rest to lock the slide when said back rest is in rear upright position.

MARTIN FOX.
